Primary Examiner — Jonathan J Han*Assistant Examiner* — Molly K. Orzechowski(74) *Attorney, Agent, or Firm* — Banner & Witcoff, Ltd.**(57) CLAIM**

The ornamental design for a shoe as shown and described.

DESCRIPTION

FIG. 1 is a front perspective view of a shoe showing my new design;

FIG. 2 is a side view thereof; and,

FIG. 3 is a rear perspective view thereof.

The broken line immediately adjacent to the bottom of the front shaded area defines the bounds of the claimed design and forms no part thereof. The broken line showing of the regions within the shaded areas form no part of the claimed design. The broken lines depicting the remainder of the shoe form no part of the claimed design.
